CLAIM

The ornamental design for a stroller tray, substantially as shown and described.

DESCRIPTION

FIG. 1 is a perspective view of the stroller tray in accordance with the present invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of the stroller tray with coiled arms in accordance with the present invention.

The present invention includes the exterior design of the stroller tray and arms. Any cup holders or other compartments shown in the Figures and any other portions of the Figures shown in broken lines are for illustration only and form no part of the claimed design.

1 Claim, 6 Drawing Sheets
